UNITED STATES PATENT OFFICE

HENRY E. BRANDT, OF ST. PAUL, MINNESOTA, ASSIGNOR TO THE DOBBINS MANUFACTURING COMPANY, NORTH ST. PAUL, MINNESOTA, A CORPORATION OF SOUTH DAKOTA

SPRAYER CONSTRUCTION

Application filed August 23, 1928. Serial No. 301,589.

This invention relates to a sprayer and while the sprayer may be used to spray various liquids or substances it is particularly designed for spraying insecticides. It is desirable in a sprayer structure to have the valve mechanism employed accessible from the outer side of the sprayer so that it can be readily removed or examined. It is also desirable to have the discharge tube through which the material is supplied, which is usually quite small, so arranged that it can be removed so as to be cleaned of obstructions when necessary.

It is an object of this invention, therefore, to provide a simple and efficient construction of sprayer having a compressed air chamber with means for forcing air thereinto and a valve controlling communication between said chamber and means, which valve is accessible from the outer side of said sprayer.

It is another object of the invention to provide a sprayer having a small discharge tube which is constructed and arranged to be readily removed and cleaned if necessary.

It is still another object of the invention to provide a sprayer having a liquid receptacle and an air chamber, a spout leading from said air chamber, a discharge tube held in said spout and a nozzle adjustable in relation to said spout and tube.

These and other objects and advantages of the invention will be fully set forth in the following description made in connection with the accompanying drawings in which like reference characters refer to similar parts throughout the several views and in which,

Fig. 1 is a longitudinal central section of the sprayer;

Fig. 2 is a top plan view of the sprayer, certain portions being broken away and others shown in horizontal section;

Fig. 3 is a horizontal section taken on the line 3—3 of Fig. 1, as indicated by the arrow;

Fig. 4 is a vertical section taken on line 4—4 of Fig. 1, as indicated by the arrow;

Fig. 5 is a vertical section taken on line 5—5 of Fig. 3; as indicated by the arrow; and

Fig. 6 is a perspective view of the discharge pipe removed from the sprayer.

Referring to the drawings, a sprayer is shown comprising a liquid receptacle 10. While the receptacle may be made of different shapes, in the embodiment of the invention illustrated, it is shown as substantially cylindrical, the same being so disposed as ordinarily to rest on one longitudinal side. Said receptacle has a filling opening in its top closed by a cap 10a. The receptacle has extending across its top, set thereinto and secured thereto, another smaller cylindrical member 11, the axis of member 11 being disposed at right angles to the axis of receptacle 10. A diaphragm 12 in the form of a flanged circular plate fits within and extends transversely of cylinder 11 dividing the same into an air chamber 11b at the front portion and a pump cylinder 11a at the rear portion. The diaphragm 12 has a central portion provided with a semi-circular groove in which is fitted a cylindrical plug 13. Plug 13 extends through an opening in the side of cylinder 11 and has a bore 13a extending from its outer side thereinto. A smaller bore 13b extends from the bottom of bore 13a through the other end of the plug, and a valve seat is formed at the junction of said bores. A ball 14 is disposed in and movable within bore 13a and adapted to co-operate with said valve seat to close the bore 13b, diaphragm 12 and plug 13 having aligned openings at 12a communicating with bore 13a. The outer side of bore 13a is closed by a threaded screw or plug 15 threaded in the outer end of plug 13, the outer end of screw or plug 15 being slotted to effect removal thereof. The pump cylinder or chamber 11a has a plunger or piston 16 slidable therein secured to a rod 17 extending through the closing member 18 at the rear end of chamber 11a, said member 18 being held in place by screws 19 extending through cylinder 11 and into said member. Cylinder 11 has an opening 11c in the side thereof adjacent member 18. Rod 17 has a handle 20 at its outer end extending transversely thereof. Rod 17 has a plurality of small lugs 17a struck up therefrom forming stop members adapted

to engage a washer 21 at the outer side of member 18 to limit the inward movement of said rod. A washer 22 is also disposed at the inner side of member 18 against which 5 lugs 17b at the inner end of said rod 17 may engage to limit the outward movement of said rod. The front end of cylinder 11 is closed by a rounded cap 11c secured thereto which has an opening in its forward end 10 axially disposed and into which fits and is secured a spout 23 extending outwardly from said cap 11c and having a flange engaging the outer side of said cap. Cylinder 11 has an opening 11d affording communication 15 between air chamber 11b and receptacle 10 and a tube 24, shown of curved shape, extends through the spout 23 and opening 11d and to a point adjacent the bottom of receptacle 10 so as to be disposed in the liquid in 20 said receptacle. Spout 23 is threaded at its outer end and has threaded thereon a nozzle member 25 having a small central aperture 25a axially alined with spout 23 and the outer end of tube 24. Nozzle 25 preferably is 25 knurled on its periphery. A cup-like member 26 surrounds spout 23 having an open front end in which is disposed packing material 27, which bears against the rear end of nozzle 25 and the outer side of spout 23. 30 A compression coiled spring 28 surrounds spout 23 bearing at its rear end against cap 11c and at its forward end against member 27, so that said packing 27 is forced against the nozzle 25 and member 23. The tube 24 35 has secured adjacent its discharge end a U-shaped clip 29, having spaced cylindrical side portions 29a to frictionally engage the inner side of spout 23, member 29 being somewhat resilient, and the front substantially square. 40 portion thereof forming a stop.

In operation, material to be sprayed will be placed in receptacle 10 and the parts assembled as shown in Fig. 1. Upon reciprocation of the pump rod 17 air will be drawn 45 into the cylinder 11 into the portion 11a thereof and forced through the bore 13b and openings 12a into chamber 11b. Air pressure accumulates in chamber 11b and in the receptacle 10. This pressure acting on the liquid 50 in receptacle 10, forces the same upward through tube 24. As the liquid passes from said tube it is met by air forced through the spout 23 and this air and liquid commingle and are sprayed through the opening 25a so 55 that the liquid is broken up into a fine mist and discharged in a shower with the air. The character of the shower can be varied by adjustment of nozzle 25. The passage of any liquid around spout 23 is prevented by the 60 packing 27. The packing engaging the nozzle 25 also holds said nozzle in its adjusted position. The tube 24, as shown is curved and if the same should become obstructed it can be removed by removing cap 25 and then with- 65 drawing the tube through spout 23. The

tube 24 normally is held in central position in spout 23 by the clip 29, which is removable with the tube. It will be seen that if it is desired to remove or inspect the valve-plug 13 and valve 14 this can be done by merely removing the screw or plug 15. 70

From the above description it is seen that applicant has provided a very simple and efficient sprayer and one that can be easily and inexpensively made. The valve part is quite 75 accessible and the discharge tube can be easily and quickly removed and cleaned. The adjustable nozzle is easily and quickly adjusted and held in adjusted position.

It will, of course, be understood that various changes may be made in the form, details, proportions and arrangement of parts without departing from the scope of the invention, which, generally stated, consists in the novel parts and combinations of parts 85 disclosed and defined in the appended claims.

What is claimed is:

1. A sprayer having in combination, a liquid receptacle, an air chamber having an opening communicating with said receptacle, 90 a discharge spout extending from said air chamber, a tube extending through said spout and said opening into said receptacle and a clip having spaced outwardly disposed semi-cylindrical portions fitting in said spout and 95 secured to the discharge end of said tube and frictionally engaging the wall of said spout to hold said tube in proper position therein.

2. A sprayer having in combination a liquid receptacle, an air chamber having an opening communicating with said receptacle, 100 a discharge spout extending from said air chamber, a tube extending through said spout and said opening into said receptacle, and a spring clip of substantially 105 U-shape through which said tube extends and disposed in said spout adjacent the discharge end of said tube and having arms frictionally engaging the wall of said spout to hold said tube in proper position therein. 110

In testimony whereof I affix my signature.

HENRY E. BRANDT.
